UNITED STATES PATENT OFFICE

ANDREW R. CAMPER, OF ROANOKE, VIRGINIA

SLUG-CASTING MOLD

Application filed June 11, 1929. Serial No. 370,080.

This invention relates to certain improvements in casting means for linotype and the like associated with typographical composing machines, where matrices are released from a magazine, or other device, by means of a keyboard or the like and assembled in lines of various lengths and sizes of characters in the molds of said machines, where a melting pot is arranged to deliver molten metal into said molds up against the composed or assembled line of matrices to produce a type bar or slug in the usual manner.

Modern stereotyping and printing methods and machinery, are placing heavy burdens on the product of linotype and type casting machines, requiring lines, bars and slugs of greater strength and durability. The constant increase in size of type characters and the great possibilities for the future, demand that better means be provided for producing more desirable type bars and slugs sufficiently strong and durable to properly support the printing surface of such type characters, bars, slugs and lines.

It is the object of the present invention to provide a mold that will cast an improved linotype having one side wall of sufficient strength, with ribs or braces cast thereon to properly support the center, and an overhanging face or ledge whereby the face will have a greater width than the body to permit the introduction of a flat slug or bar similar to a spacing bar, beneath this overhanging ledge to provide in reality another side wall, whereby the printing surface along this edge will be sufficiently reinforced to withstand repeated use without the usual sagging or caving in of the type face.

Particularly, the present invention relates to a novel form of mold, and also a novel form of type bar produced by said mold, whereby the type bar will be provided with the usual supporting ribs, and in addition, an overhanging face or ledge for the reception of a bar or slug to reinforce the printing face along this edge of the type bar and to give proper and sufficient support and strength at this usually weak point, and thus prevent sunken and caved in characters of

such linotype bars or slugs upon repeated use of said linotype.

As hereinbefore stated, in the casting of the present form of linotype it is customary to provide a wall along one face of the bar and in combination with the wall or face a series of vertically disposed reinforcing ribs. These ribs are the full width of the face of the type bar so that the present molds for casting this linotype are provided with a head-piece which in turn is constructed with a serrated or notched portion projecting into the mold cavity, said head-piece also being provided with a flange defining one side edge of the type bar, the other side edge of the type bar being defined by that portion of the main body portion of the mold forming the mold cavity. In these previously constructed molds the serrations or notched portions extend to the aforesaid flange so that the reinforcing ribs in the type bar when cast likewise extend to the adjacent edge of the type bar and the full width of the face.

In applicant's construction his improved mold is so formed, with particular reference to the head-piece, that these spaced reinforcing ribs do not extend the full width of the face of the type bar whereby there is produced an overhanging flange along that side of the type bar opposite to the side provided with the continuous wall. With this construction of type bar a flat slug or spacing bar may be positioned along this edge of the type beneath the overhanging flange of the type face providing substantially a second solid wall for supporting this entire edge of the type bar. This improved linotype or type bar is produced by a very simple yet ingenious change in the construction of the present form of linotype mold. This change or improvement is produced by simply shortening the serrations or grooves in the mold head-piece or cap so that they do not extend the full width of the mold cavity, as will be explained more fully in the detailed description to follow.

The present invention also contemplates in some instances, where an unusually wide slug or type bar is desired, the idea of providing the body portion of the mold, adjacent

the mold cavity, with a similar arrangement of longitudinal recess and serrations whereby the type bar cast in such a mold will be provided with a central longitudinal wall and oppositely disposed transverse reinforcing ribs, the opposite side edges of the type face overhanging, providing for the insertion under both overhanging edges, of a spacing bar or slug, to reinforce these edges in a manner to be hereinafter more fully described.

In the accompanying drawings:

Figure 1 illustrates in elevation, the preferred form of the invention wherein the same is applied to the cap portion of the mold;

Fig. 2 is a vertical sectional view;

Fig. 3 is a partial perspective view;

Fig. 4 illustrates the form of linotype or slug produced by the mold; and

Fig. 5 shows a vertical sectional view of the improved type bar in its assembled form with the spacing bar or slug inserted under the overhanging edge;

Fig. 6 is a view in elevation showing the invention as applied to both the cap portion and the main body portion;

Fig. 7 is a vertical sectional view thereof;

Fig. 8 is a partial view in perspective;

Fig. 9 illustrates the form of linotype or type bar produced by the form of mold as shown in Fig. 6; and

Fig. 10 is a cross sectional view of this type bar illustrating the manner of setting up the same in combination with the spacing bars or slugs inserted under the opposite overhanging edges of the type face.

Referring to the drawings in detail with particular reference to Fig. 1, 1 illustrates the body portion of the usual type of linotype mold and 2 represents the cap portion properly spaced from the body portion by the conventional liners 3 and 4, all of which construction with the exception of certain details of the cap portion to be hereinafter more fully described, represents the well known construction of linotype mold.

The cap portion 2 in the present instance of this improved mold is provided with a longitudinal rib 5 and inwardly projecting blocks or core sections 6 formed by spaced transverse grooves 7.

These grooves 7, it will be noted, do not extend to the longitudinal rib 5 but are foreshortened or terminated in order to leave a space 8 between the end of the grooves and the longitudinal rib 5, whereby a longitudinal recess or the like 9 will be produced. With this construction of mold, with the particular improvement above referred to, a linotype or slug will be cast having the usual side wall 10 but with foreshortened transverse reinforcing ribs 11 resulting in a type face having a longitudinal overhanging flange or ledge 12 under which flange 12 is adapted to be inserted or placed a spacing bar or

slug 13 in the setting up of the type bar whereby this overhanging edge will be properly supported and reinforced as clearly illustrated in Figs. 4 and 5 of the drawing.

Where it is desirable and necessary to cast a linotype or slug having an unusually wide type face, the construction or mold as shown in Fig. 6 is provided wherein, similar to the cap portion, the main body portion of the mold is constructed with spaced blocks or core sections 14 produced by spaced foreshortened transverse grooves 15 in the same manner as previously described with respect to the cap portion. This construction will provide a longitudinal recess 16 along that part of the body portion defining one side of the mold cavity. With this construction a type of slug or type bar as shown in Figs. 9 and 10 will be produced having a central longitudinal wall 17 and oppositely disposed transverse foreshortened ribs 18 wherein the opposite edges of the type face 19 will overhang or result in the overhanging flanges or the like 20. With this construction two spacer bars or slugs 21 are used as clearly shown in Fig. 10 of the drawings.

By means of this invention it will be obvious that not only many type bars or slugs can be cast with enlarged printing characters, with the greatest facility, but that the bars or slugs formed in this manner are of superior quality, strength and durability by reason of the solid support afforded to the characters along both edges of the face thereof, and it will be observed that the form of mold as disclosed in the instant application not only distinguishes from all prior types of molds, but the particular linotype cast in this mold is likewise distinctive.

The present invention has been shown merely in its preferred forms and by way of example, and as applied to a particular type of mold, but obviously many variations and alterations may be made, and the invention is not to be limited to any specific form or embodiment except insofar as such limitations are defined in the claims.

What I claim is:

1. A slug casting mold comprising a main body portion, a cap portion, and intermediate liners defining the mold cavity, the inner face of said cap being provided with a series of transverse notches producing spaced blocks or core sections extending into the mold cavity, said transverse notches intermediate the core sections terminating short of the top edge of the mold cavity.

2. A slug casting mold comprising a main body portion, a cap portion, and intermediate liners defining the mold cavity the inner face of said cap and main body portion being provided with a series of transverse notches producing spaced blocks or core sections extending into the mold cavity said

transverse notches terminating short of the top and bottom edges of the mold cavity.

3. A slug casting mold comprising a main body portion, a cap portion, and intermediate 5 liners defining the mold cavity, the inner face of said cap being provided with a longitudinal flange and a series of transverse notches producing spaced blocks or core sections extending from said flange into the mold cavity, said notches terminating short of said flange, whereby a continuous and uninterrupted longitudinal recess is produced adjacent the longitudinal flange.

4. A slug casting mold comprising a main 15 body portion, a cap portion, and intermediate liners defining the mold cavity, the inner faces of said cap and main body portion being provided with a longitudinal flange and a series of transverse notches producing spaced 20 blocks or core sections extending from said respective flanges into the mold cavity, said notches terminating short of their respective flanges whereby a continuous and uninterrupted longitudinal recess is produced adjacent 25 each longitudinal flange of the cap and main body portion respectively.

5. A slug casting mold comprising a main body portion, a cap portion and intermediate liners defining the mold cavity, the inner face 30 of said cap being provided with a series of transverse notches producing spaced blocks or core sections extending into the mold cavity, said transverse notches intermediate the core sections terminating short of the top 35 edge of the mold cavity, whereby said mold is adapted to cast a linotype having a longitudinal wall, spaced transverse ribs and a face portion, said face portion being of greater width than the width of the transverse ribs 40 and extending beyond and overhanging said ribs, in a manner to receive under the overhanging portion a spacer bar or slug to reinforce said overhanging portion.

6. A slug casting mold comprising a main 45 body portion, a cap portion, and intermediate liners defining the mold cavity, the inner face of said cap and main body portions being provided with a series of transverse notches producing spaced blocks or core sections extending 50 into the mold cavity, said transverse notches terminating short of the top and bottom edges of the mold cavity, whereby said mold is adapted to cast a linotype having a central longitudinal wall, spaced transverse 55 ribs and a face portion, said face portion being of greater width than the width of the transverse ribs and extending beyond and overhanging said ribs, in a manner to receive under the overhanging portion a spacer 60 bar or slug to reinforce said overhanging portion.

7. A slug casting mold comprising a main body portion, a cap portion, and intermediate liners defining the mold cavity, the inner 65 face of said cap being provided with a longi-

tudinal flange and a series of transverse notches producing spaced blocks or core sections extending from said flange into the mold cavity, said notches terminating short of said flanges, producing a continuous and uninterrupted longitudinal recess adjacent the longitudinal flange, whereby said mold is adapted to cast a linotype having a longitudinal wall, spaced transverse ribs and a face portion, said face portion being of greater width than the width of the transverse ribs, the full thickness of said face portion extending beyond and overhanging said ribs, in a manner to receive under the overhanging portion, a spacer bar or slug to reinforce said overhanging portion. 70

8. A slug casting mold comprising a main body portion, a cap portion, and intermediate liners defining the mold cavity, the inner faces of said cap and main body portion being provided with a longitudinal flange and a series of transverse notches producing spaced blocks or core sections extending from said respective flanges into the mold cavity, said notches terminating short of their respective flanges producing a continuous and uninterrupted longitudinal recess adjacent each longitudinal flange of the cap and main body portion respectively, whereby said mold is adapted to cast a linotype having a central longitudinal wall, spaced transverse ribs on opposite sides of said wall and a face portion, said face portion being of greater width than the width of the transverse ribs, the full thickness of said face portion extending beyond and overhanging said ribs, in a manner to receive under the overhanging portions, spacer bars or slugs to reinforce said overhanging portions. 85

In testimony whereof I affix my signature. 90
